CLAIM

The ornamental design for a connector as shown and described.

DESCRIPTION

FIG. 1 is a front bottom left perspective view of a connector showing our new design;

FIG. 2 is a rear top left perspective view thereof;

FIG. 3 is a rear bottom left perspective view thereof;

FIG. 4 is a front view thereof;

FIG. 5 is a rear view thereof;

FIG. 6 is a right side view thereof;

FIG. 7 is a left side view thereof;

FIG. 8 is a top view thereof; and,

FIG. 9 is a bottom view thereof.

The uneven-length broken lines immediately adjacent to the shaded areas define the bounds of the claimed design and form no part thereof. The remaining even-length broken lines represent portions of the connector that form no part of the claimed design.
